(57) CLAIM

The ornamental design for a compression tank top undershirt with waist pockets, as shown and described.

DESCRIPTION

FIG. 1 is a front view of the compression tank top undershirt with waist pockets on both the left and right side of the waist.

FIG. 2 is a rear view of the claimed design.

FIG. 3 is a right side view of the claimed design.

FIG. 4 is a left side view of the claimed design.

FIG. 5 is a top view of the claimed design; and,

FIG. 6 is a bottom view of the claimed design.

The evenly dashed broken lines along the surfaces of the compression tank top undershirt with waist pockets depict stitching that forms part of the claimed design.

The stippling technique in the drawings shows a contrast in appearance and does not reflect a particular surface color or material.
